Homer L. Rogers Inventor
By his Attorney
Teal & Miller

UNITED STATES PATENT OFFICE

HOMER L. ROGERS, OF CINCINNATI, OHIO, ASSIGNOR TO THE PHILIP CAREY MANUFACTURING COMPANY, A CORPORATION OF OHIO

TRUNK CONDUIT

Application filed October 19, 1927. Serial No. 227,324.

My invention relates to trunking or conduits for carrying cables, signal wires and other lines of cables or wires that it is desired to enclose for protective purposes.

5 My invention is shown in the attached drawings in which:

Fig. 1 is a perspective view showing my conduit with the lid or top slightly elevated to more clearly show the same, and Fig. 2 is 10 a side view of a modification.

In the drawings, A is the trunking or conduit proper, and B the cover for same. My improved conduit or trunking is made from a composition consisting of a homogeneous 15 mass of bitumen and filler such as a fibrous filler or a mineral either granular or pulverulent or a combination of both granular and fibrous filler. In the preferred form of my invention I mix with a minor proportion of bitumen, preferably asphalt of a suitable 20 melting point preferably one ranging from 150 deg. to 275 deg. F., a quantity of mineral either in the form of a pulverulent material 25 or a comparatively small granular material or both in excess of the asphalt used and a fibrous material in less proportion than the asphalt. I have found that a satisfactory 30 mix may be made by using approximately 45 to 55 per cent mineral, 30 to 40 per cent asphalt and the balance fibre. This material is 35 mixed while the asphalt is heated until a homogeneous mass has been formed and then before the mass has cooled and while in a plastic state it is moulded under pressure to 40 form my conduit which consists of the body A provided with the bottom 1, the vertical sides 2, 2 and the top B. The top B is provided with a portion 3 in the form of a 45 tongue which projects down between the vertical sides 2, 2 of the body A so as to hold the top in fixed position on the body A. My 50 conduit may be made having the body A and the top B of the same length, or if desired one or the other may be longer as shown for instance in Fig. 2 where the top is longer than the body A and by reason of its being longer it will, when laid, hold the body A of the various sections in alignment and in fixed 55 position with respect to each other by the nails 4, 4 which may be readily driven through

the top into the body of my conduit. The character of my conduit is such that nails or bolts may be readily inserted into same without fracture and such nails or bolts will be held firmly therein because of the tenacious 55 character of the material of my conduit. I also provide where desired, dowels or pins 5 connecting the body portions A of adjacent conduits, which dowels or pins 5 are driven into openings 6 which may be preformed or may be formed by the dowels, pins, etc. in the body A. For some purposes in installing my conduit I apply to the adjacent ends of the bodies A, a solvent for the bituminous material or a coating of a bituminous 60 material so as to cement the adjacent body portions together and a similar solvent or coating may be applied on the tops of the vertical sides 2, 2 or on the adjacent covers of the portion B or both, for the purpose of 65 holding the cover in adhesive engagement with the body A of my conduit.

While I have stated the preferred method of making my conduit and the preferred mix of the various materials, giving quantities 75 thereof, I do not want to be limited to such specific combinations as minor changes may be made without departing from my invention.

As will be readily seen from the foregoing, 80 any number of the body portions A of my conduit may be laid, the cables placed therein and then the top or cover portion B attached to enclose the cables. If it is desired 85 to remove, replace or repair cables, the cover may be readily removed for that purpose without removing the body portion A. It will also be seen that by virtue of the character of my materials, my conduit may be 90 laid in the open or laid under ground if desired and it will form a water-proof conduit. Also affords electrical insulation and will not damage or affect the cables laid in it and in fact forms an insulation for the cables 95 against any elements that would tend to affect or injure same.

Claims:

1. A conduit composed of a plurality of members formed of a tenacious homogeneous mass of bituminous material and a fibrous 100

material rendering said members penetrable by nails or the like without fracture.

2. A conduit composed of a plurality of members formed of a homogeneous mass of bituminous material, a mineral and a fibrous material rendering said members penetrable by nails or the like without fracture.

3. A conduit composed of a plurality of members formed of a homogeneous mass of bituminous material, a pulverulent mineral and a fibrous material whereby said members may be and are cemented together by bituminous material and whereby said conduit is rendered electrically insulating, water-proof and air-tight.

4. A conduit consisting of a conductor receiving body and cover members composed of bituminous material and filler material such that said members may be and are secured together by effecting an adhesion between the abutting surfaces of the members.

5. A conduit comprising a body portion composed of a tenacious homogeneous mixture of bituminous material and a filler including fibrous material, a cover for said body portion, and nails driven through said cover into said body portion uniting said cover and body portions, said material composing said body portion rendering said body portion penetrable by said nails without fracture.

6. A conduit as in claim 5 in which the contacting parts of the body and cover portions are cemented together by bituminous material.

7. A conduit comprising a plurality of members composed of bituminous material and a filler including fibrous material, whereby said members may be and are cemented together by bituminous material.

8. A conduit comprising a body portion and a cover therefor composed of bituminous material and a filler including fibrous material, whereby the contacting parts of said body and cover portions may be and are cemented together by bituminous material.

9. A conduit for cables and the like consisting of a plurality of sections each having a base portion and side portions extending from said base portion and a cover for said conduit, said sections being composed of bituminous material and a filler in such proportion of bituminous material that the ends of adjacent portions of said conduit may be and are cemented together by bituminous material.

10. A conduit comprising a plurality of body and cover portions arranged end to end and formed of bituminous material and filler material, including fibrous material, whereby the contacting ends of said body and cover portions may be and are cemented together by bituminous material.

11. A conduit composed of a plurality of members formed of a homogeneous mass

comprising about 45 to 55 per cent pulverulent mineral, 30 to 40 per cent asphalt and the balance fibre.

12. A conduit composed of a plurality of members formed of bituminous material and a filler including fibrous material, the proportion of fibrous material being less than that of the bituminous material.

13. A conduit composed of a plurality of members formed of asphalt and a filler including fibrous material, the proportion of fibrous material being less than that of the asphalt.

14. A conduit composed of a body having a longitudinal opening, and a cover for said opening composed of a homogeneous mass of bituminous material, a mineral and a fibrous material, rendering said cover penetrable by nails or the like without fracture.

15. A conduit composed of a waterproof body having a longitudinal opening, and a cover for said opening composed of a homogeneous mass of bituminous material, a mineral and a fibrous material, rendering said cover penetrable by nails or the like without fracture.

In testimony whereof, I have signed my name to this specification.
